UNITED STATES PATENT OFFICE.

FRANK T. NEWITT, OF PLATTEVILLE, AND SIMEON H. LA PLANT AND LEWIS I. TURNER, OF SALIDA, COLORADO, ASSIGNORS TO THE L. T. N. MANUFACTURING & DEVELOPMENT SYSTEM, OF PLATTEVILLE, COLORADO, A COMMON-LAW TRUST AGREEMENT ORGANIZED UNDER THE LAWS OF COLORADO.

APPARATUS FOR PRODUCING OIL GAS.

Application filed March 11, 1924. Serial No. 698,418.

This invention relates to a method and apparatus for producing gaseous fuel and its main object is to provide by a system of simple devices, an efficient and economical method of producing a gaseous mixture adapted for use as an illuminant or a fuel.

A further object of the invention is to utilize in the production of a gaseous mixture of the above described character the 10 exhaust gases of an internal combustion engine, and still another object resides in providing in a system of producing fuel gas, an improved manner of charging a gaseous motive fluid with volatilized hydrocarbons 15 derived from a supply of a volatile hydrocarbonaceous liquid.

Our invention broadly comprehends the provision of a chamber in which a hydrocarbonaceous liquid such as gasoline, is intimately intermixed in vapor form with the exhaust gases of an internal combustion engine, and as such, it is particularly adapted for use in connection with a power driven vehicle of the internal combustion 25 engine type.

An embodiment of our invention has been illustrated in the accompanying drawings, in the several views of which like parts are similarly designated and in which 30 Figure 1 represents a diagrammatic, partially sectional elevation of the system of co-operative devices comprised in the invention;

Figure 2, a similar elevation showing a 35 modification in the arrangement of the parts of the system;

Figure 3, an enlarged sectional elevation of the mixing chamber of the system;

Figure 4 is a detailed vertical longitudinal sectional view of one of the check valves 40 comprised in the system; and

Figure 5 is a detailed vertical longitudinal sectional view of a pressure regulating valve adapted for use in the system.

Referring to the drawings, 5 designates the 45 body element of an internal combustion engine, providing one or more piston chambers in which the explosive charges are burned for the actuation of reciprocating pistons.

Each of the cylinders is as usual equipped with a spark plug 6 and with a relief cock

7 for the escape of fuel gas compressed by movement of the respective piston.

The reference character 8 designates a 55 tank for the supply of a hydrocarbonaceous liquid fuel, such as those used in connection with automobiles of the internal combustion engine type for example, oils such as gasoline or kerosene, 9 is a mixing or gasifying chamber in which the exhaust or combustion gases from the engine are charged with hydrocarbons derived from the liquid in the reservoir 8, 10 designates a reservoir in which the oil gas produced in the gasifying chamber may be stored for future use, and 12 is a reservoir in which the exhaust gases of the engine accumulate before they pass to the gasifying chamber.

In the arrangement shown in Figure 1 of 70 the drawings, one of the relief cocks of the engine has been removed and the opening of the piston chamber in which it was attached is by means of a pipe 13 connected with an intake-opening of the reservoir 12. A check 75 valve 14 in the pipe 13 prevents the return flow of gases from the reservoir 12.

A pipe 15 connected with an outlet opening of the reservoir extends into the gasifying chamber 9 with its open end in opposed 80 relation to a nozzle 16 which by means of a pipe 17 is connected with the source of liquid fuel supply represented by the tank 8.

A pressure regulating valve 18 is interposed between the reservoir 12 and the gasifying chamber in the pipe 15, to equalize the pressure at which the exhaust gases enter the gasifying chamber, an equalizing valve 19 is for the same purpose interposed between the tank 8 and the gasifying chamber in the 90 pipe 17 and a check valve 20 connected in the same pipe prevents the return flow of fluid from the gasifying chamber to the gasoline tank.

In Figures 1 and 2, the nozzle has been 95 shown diagrammatically in a position opposite to the open end of the pipe which connects with the reservoir 12, but in Figure 3 is illustrated a preferred arrangement of the nozzle and the pipe which is conductive to 100 promoting and expediting vaporization of the hydrocarbonaceous liquid and its intermixiture with the exhaust gases.

The nozzle in the construction shown in

Figure 3, is constituted by the end of the pipe 15 leading from the tank 12, which as in the diagrammatic view, is disposed in alignment with the end of the pipe 17 connected 5 to the reservoir 8.

The nozzle extends, however, into the pipe 15 and its orifice is controlled by a tapering needle valve 21 at the end of a stem 22 which is slidably supported in a bearing 10 23.

The end portion of the pipe 15 extending into the mixing chamber, is preferably connected with the body portion of the same through the medium of an elbow 24 provided 15 with a stuffing box 25 through which the stem 22 passes for its connection with a hand lever, pedal or other device to effect its longitudinal movement for the adjustment of the valve 21 relative to the orifice of the 20 nozzle.

The valve has exteriorly of the nozzle a disk-shaped collar 26 upon which the liquid fuel discharged from the pipe 17 impinges and which causes it to be finely divided and 25 diffused into the hot exhaust or combustion gases entering the gasifying chamber through the pipe 15. The discharge end of a conduit 15 forms a tubular outlet which extends through one wall of the mixing 30 chamber and terminates short of the opposite wall through which the nozzle extends. The nozzle which is of a diameter less than that of the tubular outlet projects into the same, and the deflecting or baffle disk 26 35 which is arranged in the path of the discharge from the nozzle is of a diameter less than that of the interior of the tubular outlet and it partially constricts the same and it forms an annular space or passage between 40 its periphery and the walls of the tubular outlet. The exhaust gases pass over or across the periphery of the baffle disk or member in an annular stream against which the gasoline from the nozzle is sprayed. As 45 the outlet and the baffle are heated by the exhaust gases the gasoline is in the form of a fine spray or vapor when it commingles with the exhaust gases and as it leaves the outlet pipe into the mixing chamber it is 50 in gaseous form and thoroughly mixes with the exhaust gases in the mixing chamber.

The gasifying chamber has an outlet-opening which by means of a pipe 37 is connected with the reservoir 10, a check valve 55 40 in the pipe prevents the return flow of the oil gas to the mixing chamber, and a valve-controlled pipe 29 connected with an outlet of the reservoir 10 is provided to conduct the oil gas to the burners of a stove, 60 lamp or other similar contrivance.

It is preferred that in the operation of the system, the gasoline or other volatile liquid be forced from the tank and into the gasifying chamber under mechanical pressure. In motor vehicles equipped with the 65

so-called vacuum system, this pressure is automatically produced in the operation of the engine, but it may be obtained by the use of a pump or other similar compliance as indicated at 30 in Figure 2, or it may be supplied by connecting the upper portion of the tank with the combustion space of another piston chamber of the engine through the medium of a pipe 31 as shown in Figure 1. 70

The last mentioned method of supplying the pressure to the gasoline has the added advantage of adding to the carbonaceous fuel by any unconsumed or uncombusted fuel which may be left in the combustion 80 chamber through imperfect combustion. 75

In the operation of the system, the gasoline forcibly introduced into the gasifying chamber is brought into violent contact with the hot exhaust gases which enter the 85 chamber likewise under pressure. The impact of the two fluids causes the liquid to be finely divided and diffused in the hot gases discharged from the engine with the result that it is completely vaporized and in that condition is intimately and thoroughly intermixed with the exhaust gases. The result of the mixture thus produced is a gaseous fuel which is useful as either a 90 fuel or an illuminant. 95

By the use of a valve controlling the discharge of liquid from the nozzle, as shown at 32 in Figures 1 and 2, or as illustrated in detail in Figure 3, the richness of the mixture may be regulated according to varying 100 conditions and requirements, and it will be readily apparent that although the reservoirs 12 and 10 are advantageous and under certain circumstances indispensable, the operative condition of the system is not detrimentally impaired by placing the mixing chamber in direct connection with the exhaust opening of the engine or by conducting the mixture produced in the chamber 105 directly to the burners. 110

It will furthermore be understood that if so desired, the exhaust gases may be obtained by a suitable valve controlled connection with the exhaust-manifold of the engine and that any appliance of the general type illustrated in Figures 4 and 5 may be employed to regulate and check the flow 115 of fluids between the elements of the system as hereinbefore described.

The system illustrated in Figure 2 differs 120 from the other only in that it provides for a repeated charge of the exhaust gases with hydrocarbons derived from the liquid in the tank 8 before the mixture passes to the reservoir 10. The outlet of the primary 125 gasifying chamber is in this construction, provided with a pipe 33 which extends into a secondary gasifying chamber 34 in axial alignment with a nozzle 35 at the end of an extension 36 of the gasoline feed pipe 17 130

and an outlet of the secondary mixing chamber is connected to the storage tank by means of a pipe 37, manually adjusted valves 38 and 39 in the pipes control the flow of gases and liquid to the secondary chamber and a check valve 40 prevents the return flow of gases from the reservoir 10 as before.

While our process and apparatus as above described, are particularly adapted for the production of gas suitable for use as a fuel in heater or stoves and other similar appliances, or as an illuminant in lamps, it will be evident that under favorable conditions it may also be employed as an explosion mixture for use in the operation of an internal combustion engine.

Having thus described our invention, what we claim and desire to secure by Letters Patent is:

1. An apparatus for producing oil gas including in combination; an oil gasifying chamber, an oil tank, an oil conduit leading from the storage tank to the gasifying chamber, a combustion gas conduit leading from a combustion chamber of an internal combustion engine to the oil gasifying chamber, said combustion gas conduit having an open tubular outlet extending into the gasifying chamber through one wall thereof and terminating short of an opposite wall, a nozzle connected to the end of the oil conduit and extending through the said opposite wall of the gasifying chamber and discharging into the combustion gas tubular outlet, and an oil gas outlet leading from the gasifying chamber.

2. An apparatus for producing oil gas including in combination; an oil gasifying chamber, an oil tank, an oil conduit leading from the storage tank to the gasifying chamber, a combustion gas conduit leading from a combustion chamber of an internal combustion engine to the oil gasifying chamber, said combustion gas conduit having an open tubular outlet extending into the gasifying chamber through one wall thereof and terminating short of an opposite wall, a nozzle connected to the end of the oil conduit and extending through the said opposite wall of the gasifying chamber, a valve controlling the discharge from the said nozzle and having a baffle of less diameter than the tubular outlet and partially constricting the same and forming a passage between its periphery and the said tubular outlet, said baffle being arranged in the path of the discharge of the nozzle.

3. An apparatus for producing oil gas including in combination; an oil gasifying chamber, an oil tank, an oil conduit leading from the storage tank to the gasifying chamber, a combustion gas conduit leading from a combustion chamber of an internal combustion engine to the oil gasifying chamber,

said combustion gas conduit having an open tubular outlet extending into the gasifying chamber through one wall thereof and terminating short of an opposite wall, a nozzle connected to the end of the oil conduit and extending through the said opposite wall of the gasifying chamber, a valve extending into said nozzle for controlling the discharge therefrom and having a stem provided with a baffle member of less diameter than the tubular outlet and partially constricting the same and forming a passage between its periphery and the said tubular outlet, said baffle member being arranged in the path of the discharge of the nozzle.

4. An apparatus for producing oil gas including in combination; an oil gasifying chamber, an oil tank, an oil conduit leading from the storage tank to the gasifying chamber, a combustion gas conduit leading from a combustion chamber of an internal combustion engine to the oil gasifying chamber, said combustion gas conduit having an open tubular outlet extending into the gasifying chamber through one wall thereof and terminating short of an opposite wall, a nozzle connected to the end of the oil conduit and extending through the said opposite wall of the gasifying chamber, and a valve extending into said nozzle for controlling the discharge thereof and having a stem arranged within and extending along the tubular outlet to the exterior thereof, said stem being provided with a baffle disk of less diameter than the tubular outlet and partially constricting the same and forming an annular passage around it.

5. An apparatus for producing oil gas including in combination an oil gasifying chamber, a conduit for combustion gases extending through one wall of the gasifying chamber and terminating short of the opposite wall, a nozzle extending through the latter wall and being of less diameter than the combustion gas conduit and projecting into the same for discharging oil into the combustion gas conduit in a direction counter to the direction of the combustion gases, a valve for controlling the discharge of oil, said valve having a stem extending through the combustion gas conduit, and a baffle mounted on the stem and located within the combustion gas conduit in front of the discharge nozzle and being of a diameter less than the combustion gas conduit to provide an intervening space between its periphery and the combustion gas conduit and adapted to cause oil to be sprayed into the combustion gases passing through the combustion gas conduit.

In testimony whereof we have affixed our signatures.
